United States Patent Office

Des. 206,401
Patented Dec. 6, 1966

206,401

HANGER FOR HEATING WIRE

Joseph B. Fisher, Pittsburgh, Pa., assignor to Edwin L. Wiegand Company, Pittsburgh, Pa.

Filed Feb. 14, 1966, Ser. No. 1,016

Term of patent 14 years

(Cl. D54—1)

FIGURES 1 and 2 are plan and side views, respectively, showing my new design, and

FIGURE 3 is an enlarged section taken on the line 3—3 of FIGURE 1.

I claim:

The ornamental design for a hanger for heating wire, substantially as shown.
